UNITED STATES PATENT OFFICE

ROMAN TSCHENDA, OF WEST HOBOKEN, NEW JERSEY.

COMBINED BOWLING-ALLEY AND TABLE.

SPECIFICATION forming part of Letters Patent No. 638,486, dated December 5, 1899.

Application filed December 17, 1898. Serial No. 699,578. (No model.)

To all whom it may concern:

Be it known that I, ROMAN TSCHENDA, a citizen of the United States, residing at West Hoboken, in the county of Hudson and State 5 of New Jersey, have invented a new and useful Improvement in a Combined Bowling-Alley and Table, of which the following is a specification.

This invention relates generally to game 10 apparatus, and more particularly to a combined bowling-alley and table, the object being to provide a household game apparatus combining a flat-top table and a miniature bowling-alley.

15 Another object of the invention is to provide a table and bowling-alley which can be adjusted to a level position by raising or lowering one or more of the legs of the table.

Another object of the invention is to so construct the parts of the bowling apparatus that access can be had to all parts thereof, so that in case the ball becomes lodged it can be easily removed.

Another object is to provide a score-slate 25 which also serves as a cover for the receptacle intended to hold the balls or pins.

With these objects in view the invention consists in the peculiarities of construction and novelties of combination, all of which 30 will be fully described hereinafter and pointed out in the claim.

In the drawings forming part of this specification, Figure 1 is a top plan view of the bowling-alley appliance, the top of the table 35 having been removed. Fig. 2 is a vertical longitudinal section of the device on the line 2 2 of Fig. 1, the top of the table being in place. Fig. 3 is a section on the line 3 3 of Fig. 2. Fig. 4 is a section on the line 4 4 of Fig. 1. Fig. 5 is a detail view showing the manner of adjusting the table-legs, and Fig. 6 is a detail view of the cue.

In carrying out my invention I employ a box-like frame A, having the legs A' fitted 45 into the corner-blocks of the box-like frame, said legs having reduced upper ends provided with ferrules, and they also carry a threaded bolt B, which engages a nut C, located in the recess in the end corner-blocks, and by means 50 of the screw bolt and nut the legs can be adjusted so that the table can be regulated as desired and always maintained in a level po-

sition, spirit-levels being arranged upon the sides and ends of the box-like frame in order to show when the table has been adjusted to 55 a level position. Within the box-like frame is arranged a runway D for the balls, said runway having an incline D' at the starting-point, and is curved, as shown at D², said curve extending entirely across the box-like frame, 60

and is curved sharply, as shown at D³, so as to open upon the longitudinal center of the device, and the bottom of the runway at this point is level with a platform E, which is arranged upon the bottom of the box-like frame and 65 serves as a bed upon which the pins F are arranged and down which the balls G are projected for the purpose of striking the pins. This bed or platform E does not extend entirely across the bottom of the box, but leaves 70

the alley-ways E' upon opposite sides between it and the runway. At the end a clear space E² is also provided, into which pins can fall after being knocked down. The ball G is started down the incline and projected forcibly through the runway by means of a cue H, and as it emerges through the end of the runway it is projected down the bed or platform E in direct line with the pins, which are arranged at the rear end of said bed or platform. 75

In order to provide for the return of the balls, I arrange an inclined strip upon one side of the runway, which strip extends directly over one of the alley-ways or gutters and is inclined from the rear end to the forward end, 80

so that the ball placed therein will be discharged at the front end of the frame, as shown in Fig. 1, said strip having its upper face curved, as shown at I', for the purpose of guiding the ball. The space at the rear end 85 of the frame and runway is covered by means of a hinged board K, and the forward end of the runway and the space L is covered by means of a board M, carrying the slates N, upon which the scores can be kept. The space 90 L and the semicircular space L' are adapted to receive the balls and pins, and when the score-slate is turned down the balls and pins will be hidden from view.

This device being adapted for household 100 use is preferably constructed with a flat top, which is reinforced to prevent warping, and when fitted to the box-frame serves the purpose of an ordinary table and at the same

time entirely covers the bowling apparatus and prevents the accumulation of dust and dirt.

By means of a device constructed in this manner it is obvious that the table can be used for any household purpose and by removing the top the game apparatus is ready for use. The manner of playing or using the apparatus is obvious to every one, and a further description is not deemed necessary.

Having thus fully described my invention, what I claim as new, and desire to secure by Letters Patent of the United States, is—

In a game apparatus, the combination with

a casing of a central, longitudinally-arranged, 15 raised platform secured to the bottom of said casing having side alleys E' on either side thereof, of the inclosed inclined alley D terminating in a sharp crook or turn D³ opening upon the longitudinal center of the raised platform or pin-bed, and the return inclined gutters I, secured to the inner longitudinal side of the alley D above the side alleys E', substantially as shown and described.

ROMAN TSCHENDA.
